FOREIGN PATENT DOCUMENTS

GB 2381728 5/2003

Primary Examiner — Susan Moon Lee(74) *Attorney, Agent, or Firm* — Head, Johnson & Kachigian, P.C.(57) **CLAIM**

The ornamental design for elevated pet feeder bowls, as shown and described.

DESCRIPTION

FIG. 1 is a perspective view of the elevated pet feeder bowls, shown in place in an elevated pet feeder base for environmental purposes;

FIG. 2 is a perspective view of the elevated pet feeder bowls of FIG. 1;

FIG. 3 is a bottom view of the elevated pet feeder bowls of FIG. 1;

FIG. 4 is a front view of the elevated pet feeder bowls of FIG. 1, where the back view is the mirror image of the front view;

FIG. 5 is a top view of the elevated pet feeder bowls of FIG. 1;

FIG. 6 is a left side view of the elevated pet feeder bowls of FIG. 1; and,

FIG. 7 is a right side view of the elevated pet feeder bowls of FIG. 1.

The elevated pet feeder base shown in broken lines in FIGS. 1 through 7 is for environmental purposes only and forms no part of the claimed design.
